UNITED STATES PATENT OFFICE.

GILBERT E. BOGART AND GEORGE L. BOGART, OF SOUTH NORWALK, CONNECTICUT.

BLACKING-CABINET.

SPECIFICATION forming part of Letters Patent No. 439,831, dated November 4, 1890.

Application filed May 26, 1890. Serial No. 353,117. (No model.)

To all whom it may concern:

Be it known that we, GILBERT E. BOGART and GEORGE L. BOGART, citizens of the United States, residing at South Norwalk, in the 5 county of Fairfield and State of Connecticut, have invented certain new and useful Improvements in Blacking-Cabinets; and we do hereby declare the following to be a full, clear, and exact description of the invention, such 10 as will enable others skilled in the art to which it appertains to make and use the same.

Our invention has for its object to produce a blacking-cabinet which shall be simple and 15 inexpensive to manufacture, compact, adapted to be rigidly fixed in position upon a wall, and which when closed shall be entirely out of the way.

With these ends in view we have devised 20 the novel wall-cabinet, of which the following description, in connection with the accompanying drawings, is a specification, numbers being used to denote the several parts.

Figure 1 is a perspective of the cabinet 25 in the open position; Fig. 2, a perspective showing the cabinet in closed position; Fig. 3, a side elevation, on an enlarged scale, of the swinging blacking-holder and the plate to which it is pivoted, the parts being in the 30 open position and the back of the cabinet showing in section; Fig. 4, a similar view showing the parts in the closed position, both views illustrating the manner in which a box of blacking is held; Fig. 5, a plan view of the 35 holder, the box of blacking being removed; and Fig. 6 is a partial side elevation showing the door and swinging rest in the open position.

1 denotes the cabinet, which may be made 40 of metal or wood, but is ordinarily made of wood, and is adapted to be secured in place upon the wall by screws or bolts passing through holes in ears 2 at the top and bottom. The outer face of the cabinet consists of a 45 door 3, which is provided with internal hinges at the bottom, as shown in Fig. 1, the door when closed preferably passing within the sides, as is clearly shown in Fig. 2, leaving the outer surface of the door flush with the 50 side pieces of the cabinet. The door is fastened in the closed position by any suitable

catch 4, which may be a spring-bolt, hook, or latch of any sort, but is preferably self-acting. Upon the outer face of the door is pivoted a swinging rest 5. The cross-piece 6 55 of the rest is provided with trunnions 7, which engage brackets 8, secured to the outer face of the door, and the brackets are provided with stop-plates 8^a, which are adapted to be engaged by lugs 9 on the cross-piece to stop 60 the outward movement of the rest when the door is let down to the open position, as is clearly shown in Fig. 6. The swinging rest may of course be of any suitable ornamental construction, and is preferably provided at 65 its lower ends with bearing-pieces 10, which rest upon the floor when the cabinet is in the open position.

It will of course be understood that the cabinet should be placed just high enough 70 upon the wall so that in the open position the bearing-pieces will rest upon the floor, leaving the door in substantially a horizontal position, as shown in Fig. 6. Upon the inner side of the door, so as to be in convenient position for use when the door is in the open position, we place a foot-rest 11, and within the cabinet near the bottom thereof we provide 75 a hook 12, upon which to hang a dauber, and a suitable spring-catch 13, with which to hold 80 the polishing-brush in place, as is clearly shown in Fig. 1.

Upon the back of the cabinet we place a plate 14, having ears 14^a, to which are pivoted a swinging blacking-holder 15, the plate and 85 holder being so located in the cabinet that the holder will fold up readily within it when the door is closed, as indicated in Fig. 4. This holder consists of a suitable plate, upon which the box of blacking rests, and which is provided at its edge in the usual manner with lugs 16, against which the box of blacking rests. In order that any of the various-sized boxes of blacking may be grasped and held firmly by the holder, we provide a slide 17, 90 engaging ways 18, which is adapted to be moved up against the side of the box to clamp it firmly, as clearly shown in Figs. 3 and 4. The slide is provided with a slot 19, and a set-screw 20 passing through this slot engages the 95 holder itself and locks the slide firmly in position after adjustment. This set-screw may 100

be either a thumb-screw, as shown in Figs. 3, 4, and 5, or may be a slotted headed screw, as in Fig. 1. At the inner end of holder 15 we provide a downwardly-extending projection 5 21, which in the open position is adapted to engage plate 14, (see Fig. 3,) and upon the plate itself we also preferably form a lug 22, which is engaged by the top of the holder itself when it reaches the horizontal position, as is 10 clearly shown in Fig. 1. We thus provide a double support and stop for the holder when in the open position, so that it will rest firmly in use and also avoid danger of breakage should it drop suddenly to the open position.

15 The operation is as follows: Supposing that it is desired to use the cabinet, the operator simply releases catch 4 and allows the door to drop down to the open position, as in Figs. 1 and 6. This leaves the door in a horizontal 20 position, so that the foot-rest is in convenient position for use. As the door is dropped down, the blacking-holder also drops by gravity from the position shown in Fig. 4 to that shown in Figs. 1 and 3, so as to be in convenient position for use. As already stated, we provide a double stop for the holder, so that it rests firmly in the open position, at the same time avoiding all danger of breakage should the door be opened suddenly. The 25 30 dauber and the polishing-brush are both held in the cabinet in convenient position for use. After using, the operator replaces the polishing-brush and dauber and simply closes the door, the door itself acting to pick up the blacking-holder and carry that also to the closed position, as in Fig. 4. As soon as the

door has reached the closed position, it is locked there by catch 4, which is preferably made self-acting.

The cabinet is made deep enough in practice to just receive the dauber, polishing-brush, foot-rest, and blacking-holder easily and without crowding. It will be observed that the space is ample, so that either thick or thin boxes of blacking may be used with 45 equal convenience, and also that by means of the slide any ordinary-sized boxes may be grasped and held firmly upon the holder by the slide, this feature adding greatly to the convenience of the device in use. 50

Having thus described our invention, we claim—

A blacking-cabinet closed at the front by a door-hinge at the bottom and having on its inner side at the back a hinged blacking- 55 holder, which, when the door is closed, folds within the cabinet and when the door is opened drops to horizontal position and extends outside the cabinet and below the blacking-holder, a hook to hold a dauber, and a 60 spring-catch to hold a polishing-brush, the door having upon its inner side a foot-rest and upon its outer side a swinging rest, which supports the door and the foot-rest in the open position. 65

In testimony whereof we affix our signatures in presence of two witnesses.

GILBERT E. BOGART.
GEORGE L. BOGART.
